US0D1048906S

(12) **United States Design Patent** (10) Patent No.: **US D1,048,906 S**
(45) Date of Patent: ** Oct. 29, 2024

(54) **AUTO DIAGNOSTIC TOOL**

(71) Applicant: **AUTOPHIX TECH CO., LTD,**
Shenzhen (CN)

(72) Inventors: **Yutao Zhao**, Shenzhen (CN); **Qing Huang**, Shenzhen (CN); **Jian Hao**, Shenzhen (CN)

(73) Assignee: **AUTOPHIX TECH CO., LTD,**
Shenzhen (CN)

(**) Term: **15 Years**

(21) Appl. No.: **29/834,626**

(22) Filed: **Apr. 13, 2022**

(30) **Foreign Application Priority Data**

Dec. 15, 2021 (CN) 202130830567.2

CLAIM

The ornamental design for an auto diagnostic tool, as shown and described.

DESCRIPTION

FIG. 1 is a front perspective view of an auto diagnostic tool showing our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict the portions of the auto diagnostic tool which form no part of the claimed design.

1 Claim, 8 Drawing Sheets
